UNITED STATES PATENT OFFICE.

WILLIAM G. CLARK, OF TERRE HAUTE, INDIANA.

DRIER DRAIN SYSTEM.

No. 896,055.

Specification of Letters Patent.

Patented Aug. 11, 1908.

Application filed April 25, 1908. Serial No. 429,128.

To all whom it may concern:

Be it known that I, WILLIAM G. CLARK, a citizen of the United States, residing at Terre Haute, Vigo county, Indiana, have invented 5 certain new and useful Improvements in Drier Drain Systems, of which the following is a specification.

In steam heated driers, as employed in paper mills for instance, great difficulty is 10 experienced in getting rid of the water of condensation in the driers. Such driers are generally employed in a group involving quite a number of rotary drying cylinders and, under prevailing systems, no matter 15 what precautions may be taken, it is practically impossible to know whether or not any or all of the driers are being properly emptied of water so as to perform their proper drying duty. Traps have been introduced between 20 the individual driers and the discharge main, and glass gages on these traps indicate the level of the body of water retained in the trap, but the constancy of this level in the trap is no evidence whether a given drier is 25 working properly, or is over-charged with water, or is blowing steam through the drier without the condensation incident to the proper abstraction of heat from it.

My invention will be readily understood 30 from the following description taken in connection with the accompanying drawing in which:—

Figure 1 is a side elevation of a group of 35 drying cylinders fitted with my improved draining system: Fig. 2 a vertical longitudinal section of one end of one of the drying cylinders: and Fig. 3 a vertical longitudinal section of the neck-connections at one of the cylinders. A diversity of scales is employed 40 in the several figures of the drawing.

In the drawing:—1, indicates general frame work: 2, the cylindrical driers: 3, the necks of the driers through which the steam is injected and the water ejected: 4, the steam 45 supply main: 5, a branch pipe, one for each drier, leading from the steam supply main to the neck of the drier so as to discharge steam to the interior of the drier, these pipes being provided, as usual, with stop valves for the 50 control of the flow of steam through them: 6, the usual dip pipe in each drier, this pipe presenting its open end near the floor of the interior of the drier and passing axially through the neck of the drier, and through

the steam-way through the neck: 7, a drain 55 pipe connected with the outer end of each dip pipe: 8, a steam trap, of usual construction, at the end of each drain pipe: 9, the water discharge main which is to convey the condensed water from the driers to any desired 60 point, such as hot well or heater or boiler: 10, a funnel leading into the discharge main at each trap: and 11, a discharge spout from each trap, in position to discharge into one of the funnels.

In operation, steam from the supply main goes into and fills the driers; it parts with heat through the metal of the drier walls; condensation occurs and water accumulates in the base of the driers; the pressure of the 70 superincumbent steam in the driers forces this water outwardly through the discharge pipes and into the traps; the water accumulates in the traps; the usual float or other controlling devices in the traps causes 75 water to discharge from them when the accumulation rises above the predetermined level in the traps; the water discharging from the trap-spouts falls into the funnels and goes to the discharge main and thence away; 80 the usual glass gages on the traps indicate the level of water therein; the usual air valves on the traps provide for the discharge of air therefrom.

Steam traps are at all times liable to misbehavior and the neck connections between the drier necks and the inlet and discharge pipes are subject to disorders. These troubles are of hidden character and a mere observation of the height of water in the traps, as indicated by the gages, insures no certainty that the driers are behaving properly and working under steam or are not air bound or are not flooded. But in the present case the rate of flow of water from the individual driers can 95 be observed and the working conditions judged of, and proper conditions arranged for in case of apparent disorder. Other things being equal, a given drier if air bound will not be discharging water into its funnel 100 in proper quantity, and the same will be the case if the given drier be flooded, and the same will be the case if, by disorder of the neck-connections there be an improper direct connection between the steam inlet and the 105 water outlet. In case of any observed misperformance, as judged by the individual discharges of water, the steam may be shut

off from the appropriate drier and the defect may then be deliberately inquired into and remedied.

I claim:—

- 5 A drier drain system comprising, a plurality of rotary drying cylinders, a steam supply main, individual branch conduits leading from the steam supply main to the interior of the several driers through their necks, a
- 10 dip pipe leading from the base of each drier through the neck thereof, a water discharge pipe connected with the outer end of each dip pipe, a steam trap at the outlet end of

each water discharge pipe, a water discharge main having a receiving opening at each trap, and a discharge spout connected with each trap and open at its outer end to the atmosphere and adapted to drop its discharge into the appropriate opening in the water discharge main, combined substantially as 15 20 set forth.
